CLAIM

The ornamental design for a combined ultraviolet lamp and magnifying lens for authenticating bank notes, as shown and described.

DESCRIPTION

FIG. 1 is a front elevational of a combined ultraviolet lamp and magnifying lens for authenticating bank notes showing my new design;

FIG. 2 is a bottom plan view thereof;

FIG. 3 is a rear elevational view thereof;

FIG. 4 is a right side elevational view thereof;

FIG. 5 is a top plan view thereof;

FIG. 6 is a top plan view thereof, the illuminated magnifying head being pivoted to an alternate position;

FIG. 7 is a left side elevational view thereof;

FIG. 8 is a cross sectional view thereof as taken along line 8—8 of FIG. 1;

FIG. 9 is a cross-sectional view thereof as taken along line 9—9 of FIG. 2.

FIG. 1.

FIG. 2.

FIG. 3.

FIG. 6.

FIG. 7.
